UNITED STATES PATENT OFFICE.

ARTHUR HAMMOND SHIPLEY, OF LEICESTER, ENGLAND.

BRUSH-MAKING MACHINE.

Application filed September 10, 1920. Serial No. 409,474.

(GRANTED UNDER THE PROVISIONS OF THE ACT OF MARCH 3, 1921, 41 STAT. L., 1313.)

To all whom it may concern:

Be it known that I, ARTHUR HAMMOND SHIPLEY, subject of the King of Great Britain, residing at Leicester, in the county of 5 Leicester, England, have invented certain new and useful Improvements in or Relating to Brush-Making Machines, of which the following is a specification, reference being had therein to the accompanying drawing 10 and, for which I have applied for Letters Patent of Great Britain, May 21, 1917, which application has matured into British Patent No. 115,890, of May 21, 1917.

This invention relates to brush-making machines and concerns more particularly though not necessarily exclusively, machines for drilling or boring brush heads, backs, or stocks. The invention is applicable to brush-drilling machines of the class where 15 the stock is carried by a work-holder arranged in a rocking frame combined with which is a templet or pattern board. The said frame is movable upon a horizontal axis and vertical axis whereby the work may 20 be tilted and turned to obtain the desired spread of the holes, and it is also capable of bodily movement relatively towards and from the drill for the necessary drilling motion.

30 The present invention comprises an improvement in the mounting means of the rocking frame whereby it may be manipulated more easily for the purpose of drilling brush stocks and the adjustments necessary 35 for altering the angles of the spread of the holes may be more readily made.

According to this invention the vertical pivotal axis, upon which the frame carrying the work-holder and templet turns, is arranged upon a carriage fitted with wheels, 40 rollers or other anti-friction devices by which it may travel to and fro along a track in line with the drill. The track is formed in or on a plate movable to different positions along the bed of the machine and 45 adapted to be fastened therein by a bolt or other suitable means.

It is also a feature of the invention that the horizontal axis upon which the work 50 carrying frame is movable, is adjustable relatively to the vertical axis upon which said frame turns, by means of rack rods and gears as will be hereinafter described. The adjustment of the work holding devices 55 relatively to the said horizontal axis of the

rocking frame is also effected in a similar manner by means of rack rods and gears.

In particularly describing the invention reference will be hereinafter made to the accompanying drawings wherein a concrete 60 form of the improvements constituting an example of the invention, is shown applied to a machine for drilling or boring brush heads or stocks.

In the drawings referred to:—

65

Figure 1 is a side elevation of the machine.

Figure 2 is a plan of the same.

Figure 3 is a vertical section of the carriage and its bed taken on the line $a-a$ of 70 Figure 1.

70

Figure 4 is a sectional detail view of a fastening device hereinafter referred to.

Figure 5 is a perspective view and

Figure 6 is a vertical sectional view of the supporting means of the rack rods at the 75 horizontal axis of the rocking frame.

Figures 4, 5 and 6 are drawn to a larger scale than Figures 1, 2 and 3, and throughout the drawings like parts are designated by the same reference characters.

80

Referring to Figures 1 and 2, the brush drilling machine to which the present improvements are shown applied, comprises a bed 1 suitably supported and having thereon near one end a headstock 2 in the bearings 3 of which is rotatably mounted the drill spindle 4 the pulley 5 thereon being driven by a belt 6 from the pulley 7 on the driving shaft 8. The drill spindle is fitted with a chuck 9 to hold the drill (not shown) 90 which passes through a gauge 10 secured upon one of the bearings 3 this member being adjustable to different positions in rear of the point of the drill and serving to determine the depth of the holes formed in the 95 stock.

85

The work carrying frame comprises generally, transverse rods 11 (Figure 2), rack rods 12, an axis bar 13, rack rods 14, and a turnable bearing plate 15. The transverse rods 11 are provided thereon with work holding devices 16 of suitable form for supporting the brush head or stock these devices being adjustable along said rods to different positions to suit the size of the work 105 to be held.

100

Combined with the work carrying frame and really forming part of same is a templet 17 carried by side rods 18 which are rigid with the rack rods 12 said templet constitut- 110

110

- ing the means by which the operator manipulates the whole work carrying frame by hand for drilling the stock. The front portion of the work carrying frame constituted by the parts 11, 12, 17 and 18 is movable up and down upon horizontal axes 19 (Figures 1, 5 and 6) these being formed upon opposite ends of the axis bar 13. The whole work carrying frame is movable horizontally upon a vertical axis 20 Figures 1 and 2, which axis is arranged as will presently be described, to be capable of bodily movement in a direction longitudinally of the machine. The rising and falling fore part of the work carrying frame is held up and balanced by cords 21 (Figure 1) which pass over pulleys (not shown) and have a weight combined therewith in such a manner that free movement of the frame is permitted.
- It will be understood that the frame being movable vertically on the axes 19, horizontally on the axis 20, and longitudinally, the work can be moved about and brought into contact with the rotating drill, the position of the holes to be drilled in the stock being determined by pattern holes in the templet 17 which are employed in conjunction with a stationary point 22 (Figures 1 and 2) carried in a standard 23 fastened upon the bed 1.

According to the present invention the vertical axis 20 upon which the work carrying frame turns horizontally is arranged upon a carriage or trolley 24 (Figures 1, 2 and 3) which, in the embodiment shown, is mounted upon two wheels 25 arranged to run tandem fashion along a V track 26 formed on a plate 27 movable to different positions along the machine bed 1, said plate 27 being fastened on the bed by means of a bolt and nut 28.

- The carriage or trolley 24 is balanced and kept upright by a wheel or roller 29 on each side thereof (Figures 1 and 3) and running in contact with the underside of a fixed rail 30 attached to supports 31 on the plate 27. The wheels or rollers 29 are mounted upon an axle 32 (Figures 3 and 4) the ends 33 of which are eccentric to the centre part 32. The wheels are rotatable upon the ends 33, and the centre part 32 passes through bearing bosses 34 on the carriage 24 and is normally fastened therein but may be rotated by the application of a spanner to the squared extremity 35 for the purpose of setting the wheels up to the rails 30 to take up wear. The axle 32 may be fastened in the bearing bosses 34 by means of a clamp bolt device combined with one of said bosses. This is illustrated in Figure 4 which shows said boss in vertical section. The boss has a lug 36 formed upon one side thereof furnished with a hole disposed at right angles to the axle 32 in which hole there is arranged a clamp bolt 37 having upon it a

sleeve 38. The adjacent ends of the sleeve 38 and bolt head 39 between which there is a space are cut away at one side for the axle 32 to pass between them as shown, and when the nut 40 on the bolt is tightened the sleeve 70 is forced along the bolt and the axle is firmly clamped in the boss 34 by the wedging action of the sleeve and bolt head thereon.

The carriage or trolley 24 arranged in the manner described gives ease of movement when manipulating the work carrying frame to bring the stock into and out of engagement with the drill. This easy movement is permitted by the wheels 25 running to and fro along their tracks 26, the plate 27 being of course previously positioned on the bed 1 to suit the range of movement of the carriage.

The vertical axis 20 consists of a pin 85 firmly secured in a bossed lug 41 on the bearing plate 15 (Figure 1) said pin fitting and rotating within suitable bearing holes in the carriage or trolley 24. By preference ball bearings are provided between the carriage 90 and the bossed lug 41 to enable the bearing plate 15 to turn easily.

The bearing plate 15 has upon each side thereof bearings 42 (Figures 1, 2 and 3) through which the previously mentioned 95 rack rods 14 slide. These rods are secured to the transverse axis bar 13 and slide through the bearings 42 for the purpose of altering the position of the horizontal axes 19 and the work holding devices in relation 100 to the vertical axis 20 whereby a different angular spread of the holes in a horizontal direction may be obtained.

The adjustment of the rods 14 through the bearings 42 is brought about in the embodiment shown by means of gear wheels 43 on a spindle 44 rotatable by a hand wheel 45 in bearings 46 on the bearing plate 15, said gear wheels meshing with rack teeth formed upon the underside of the rods 14. 110 By rotating the hand wheel 45 in one direction or the other the rods 14 on opposite sides of the bearing plate 15 are simultaneously advanced or retracted as may be required and after adjustment in this manner 115 said rods may be fastened in their bearings 42 by tightening nuts 47.

As previously stated, the axes 19 upon which the fore part of the work carrying frame may be raised and lowered to tilt the stock and thereby obtain the spread of the holes in a vertical direction, are formed upon the opposite ends of the bar 13 which is attached to the rods 14. To carry the rack rods 12, the said axes 19 each have movably arranged thereon a mounting 48 (Figures 1, 2, 5 and 6) the boss 49 of which is free to turn on the axis pin 19 while through a bearing 50 the rod 12 is adapted to slide.

To facilitate the adjustment of the said 130

rods 12 through their bearings 5 whereby the position of the templet 17 and work holding devices 16 relatively to the horizontal axes is changed to vary the angle of vertical spread of the holes to be drilled, said rods have rack teeth 51 (Figure 2) formed on the top side thereof with which gear wheels 52 (Figures 1, 2 and 6) engage. These gear wheels are fast upon a transverse shaft 53 carried in bearings 54 on the mountings 48 and when rotated by means of a hand wheel 55 move both the rods 12 through the mountings to effect the desired adjustment of the parts previously mentioned. The bearing 50 is slotted at 56 (Figure 5) to expose the rod and allow the gear wheel 52 to engage with the teeth 51. The rods 12 are fastened in position in the bearings 50 after adjustment preferably by the same form of means as that previously referred to for securing the axle 32 such means consisting of a clamp bolt 57 (Figure 6), sleeve 58 and nut 59, said bolt and sleeve being located in a lug 60 (Figure 5) on the mounting 48. Similar fastening means may be used in the bearings 42 for fastening the rods 14.

By means of the gear wheels 43 and 52 and their co-operating rack teeth on the rods 14 and 12, the adjustable parts of the work carrying frame may be easily moved to any position within their respective range of movement, and it may be found convenient to use graduated markings on the said rods to enable different settings to be instantly obtained to give defined angles of spread.

What I claim then is:—

1. In a brush-making machine, in combination, a drill, a work carrying frame, a pivot upon which said work carrying frame turns, a carriage on which said pivot is mounted, a track along which said carriage travels to and fro in line with the drill, means to hold said carriage down on the track, a plate supporting said track, and a bed, said plate being movable to different positions on the bed for the purpose described.

2. In a brush-making machine, in combination, a work carrying frame, a pivot upon which said work carrying frame turns, a carriage supporting said pivot, wheels ar-

ranged in alignment with each other on the carriage and adapted to support same, a track along which said wheels travel, a roller on each side of the carriage, an overhead rail with which each roller runs in contact, and means to adjust each roller relatively to its rail, substantially as described.

3. In a brush-making machine, in combination, a work carrying frame, a pivot upon which said frame turns, a carriage supporting said pivot, wheels arranged in alignment with each other on the carriage and adapted to support same, a track along which said wheels travel, a roller on each side of the carriage, an overhead rail with which each roller runs in contact, means to adjust each roller relatively to its rail, a plate carrying the aforesaid track and rails, and a bed along which said plate is movable to different positions, substantially as described.

4. In a brush-making machine, in combination, a work carrying frame horizontal pivots upon which the forepart of said frame is movable, racks and gears to adjust said forepart in relation to said pivots, a carriage, a track along which said carriage is adapted to travel, a bearing device pivotally mounted upon the carriage, and racks and gears by which the work carrying frame is adjustable in the bearing device substantially as described.

5. In a brush-making machine, in combination, a bed, a plate movable to different positions thereon, a track and rails on said plate, a carriage, wheels thereon running in the track to support the carriage, rollers on said carriage running in contact with the aforesaid rails, a bearing device pivotally mounted on the carriage, rack rods adjustably mounted in the bearing device, gears to adjust said rack rods, an axis bar carried by said rack rods, bearings on said axis bar, a work carrying frame, racks on said frame adjustable through said bearings, and gears to adjust said racks, substantially as described.

In testimony whereof I affix my signature in presence of two witnesses.

ARTHUR HAMMOND SHIPLEY.
